[57] CLAIM

The ornamental design for a handle stud for luggage or the like, as shown and described.

DESCRIPTION

FIG. 1 is a top plan view of a handle stud for luggage or the like showing my new design;

FIG. 2 is a side elevational view as seen from the bottom of FIG. 1, the opposite side being a mirror image thereof;

FIG. 3 is an end elevational view as seen from the right of FIG. 2;

FIG. 4 is an end elevational view as seen from the left of FIG. 2; and

FIG. 5 is a bottom plan view.
